UNITED STATES PATENT OFFICE.

HENRY W. KIRCHNER, OF ST. LOUIS, MISSOURI.

METHOD AND APPARATUS FOR TRANSFERRING CONTAINERS.

Application filed January 27, 1922. Serial No. 532,245.

To all whom it may concern:

Be it known that I, HENRY W. KIRCHNER, a citizen of the United States, residing at St. Louis, Missouri, have invented a certain new and useful Improvement in Methods and Apparatus for Transferring Containers, of which the following is a full, clear, and exact description, such as will enable others skilled in the art to which it appertains to make and use the same, reference being had to the accompanying drawings, forming part of this application.

My invention relates to the transportation of merchandise and in particular to the systems of handling merchandise in which it is shipped in containers loaded by the consignor and only unloaded by the consignee; the merchandise during the shipment being transferred from warehouse to truck, to railroad car or barge, to truck and to delivery terminal in the original containers.

Such a method of transportation and the containers used therein are illustrated in prior Patent No. 1,349,209, issued to me August 10, 1920.

The object of my invention is to facilitate the transfer of the containers from the warehouse to a truck, car or barge, and vice versa.

In the accompanying drawings, which illustrate a selected embodiment of my invention, I show my apparatus and method as applied to the unloading of a container from a truck to a warehouse, and in these drawings—

Figure 1 is an elevation of the truck and inclined trackway leading into the warehouse which is sectioned to better illustrate the operation.

Figure 2 is a view showing the manner of supporting the inclined track.

Figure 3 is an enlarged view of a detail of the transfer apparatus.

Figure 4 is a view of the same detail looking at right angles to Figure 3.

Figures 5 and 6 are, respectively, side and top views of the latch shown in Figure 4.

The truck indicated at the right hand side of Figure 1 has a platform 1 upon which are mounted the box-like containers 2 and 3. The warehouse 4 is provided with a floor 5, at approximately the same level as the truck platform, although the height of this floor is immaterial, and a doorway substantially larger than the side or end of the

largest containers to be transported. An overhead track preferably consisting of a single rail 6 is suspended from the ceiling 7 of the warehouse and extends outwardly and downwardly therefrom, terminating preferably in a horizontal portion spaced some distance from the warehouse doorway and a sufficient distance above the roadway to permit the movement of a loaded truck beneath the track. Mounted upon the track is a trolley comprising wheels 9, a frame 10, a beam 11, and container engaging hooks 12 and brackets 13. The hooks 12 are pivoted on the ends of beam 11 and latches 14 are provided to engage the upper ends of hooks 12 to lock them in vertical or inclined position.

The containers 2 and 3 are provided with upstanding ears 15 provided with openings 16 adapted to receive the inwardly bent ends of hooks 12, as indicated in Figure 1. Brackets 13 are adapted to engage the top of the container, when hooks 12 are secured to the container ears, to prevent tilting of the container on the trolley relative to track 6.

When the truck is backed into the position shown in Figure 1 as many trolleys as are necessary are run out to the end of the overhead track and individually secured to the containers carried by the truck. The truck is then backed to the position indicated by the dotted lines in Figure 1. This movement of the truck carries containers 2 and 3 and their trolleys with the truck until one of the trolleys reaches the upwardly inclined portion of track 6. Continued horizontal movement of the container being due to the further backing of the truck causes the container to be lifted from the truck platform as indicated at 16 and 17, all the load now being carried by the trolleys. When the truck has pushed the containers far enough for the trolleys to have reached the upper horizontal portion of the overhead track, the containers may be manually pulled into the warehouse and run through same and an opening on the opposite side and down a similarly inclined track to a flat car or barge, or the containers may be stored in the warehouse either by leaving them suspended from track 6 or by providing dollies such as indicated at 18, in which case the trolley may be disengaged and the container moved about the warehouse independently of the overhead tracks.

It will be noted that the truck is provided with a pushing member 19 adapted to engage the side of the container and positively move the same whether or not the container is resting upon the truck platform. Member 19 is preferably provided with a roller 20 so as to offer the minimum resistance to the upward movement of the container when the incline in the track is reached. It is obvious that by properly positioning the truck, containers may be unloaded from the warehouse onto the truck without the use of a lifting derrick. Of course a railway car or other carrier may be utilized in combination 15 with the warehouse and track in the same manner as the truck shown.

Various modifications in the arrangement and in the details of my construction will be suggested and may be used without departing from the spirit of my invention, as 20 expressed in the following claims.

I claim:

1. In an overhead carrier device, a track, a trolley thereon, load suspending elements 25 on said trolley, and a load engaging bracket rigid with said trolley and adapted to contact with a load at spaced points to prevent tilting of the latter relative to said trolley.

2. In an overhead carrier device, a track, 30 a trolley thereon, elements on said trolley for pivotally suspending a load, and depending members rigid with said trolley located at opposite sides of the pivotal axis, provided by said elements, for engaging the 35 load to prevent its tilting.

3. In combination, a carrier, an overhead track having an upwardly inclined portion, a load engaging trolley mounted on said track and including pivoted hooks spaced 40 transversely of said track and adapted to swing toward each other to engage a load, and means for locking said hooks in load engaging or disengaging position.

4. In combination, a truck, merchandise 45 containers carried thereon, means for unloading said containers from said truck comprising an overhead track extending from said truck horizontally and upwardly, a

rigid container-suspending trolley on said track, and a member on said truck adapted 50 to engage a suspended container so as to push against said container to move the same and said trolley along said track so as to lift the container from the truck.

5. In a load container suspending trolley, 55 spaced wheels, a rigid frame depending therefrom, a pair of hooks for securing a container at spaced points, and a bracket extending transversely of the line between said hooks and adapted to engage a container 60 secured by said hooks to prevent tilting of the container on the trolley.

6. In combination, a truck, means for unloading containers from said truck comprising an overhead track extending from said 65 truck horizontally and upwardly, and a member on said truck adapted to engage a container which is on the truck and is secured to said trolley and to push same and said trolley along said track, thereby lifting 70 the container from said truck, said member being provided with anti-friction elements to eliminate resistance to the rise of the container when engaged therewith during the pushing operation.

7. In a load container suspending trolley, 75 a rigid frame, a pair of hooks pivoted on said frame and extending rearwardly therefrom and toward each other, and releasable means for positively holding said hooks 80 either in container engaged or in container disengaged position.

8. In an overhead transfer container for merchandise containers, a track, a traveling trolley mounted on said track at spaced 85 points to avoid tilting thereon and including rigid frame members extending longitudinally and transversely of the track, container suspending elements at the ends of one of said members, and container engaging elements at the ends of the other of said members.

In testimony whereof I hereunto affix my signature this 24th day of January, 1922.

HENRY W. KIRCHNER.
